graphie m. b. H., Berlin, Germany, a corpora-
tion of Germany

Application May 6, 1937, Serial No. 141,074
In Germany May 12, 1936

10 Claims. (Cl. 250—11)

This invention relates to a device for radio reception, particularly where ultra-short waves are used. The so-called retarding field electron discharge tube is preferably used in carrying out my invention. This tube is known to be an efficient form of detector for ultra-short wave receivers. The outstanding characteristic of my invention is that for the purpose of efficient reception and demodulation of ultra-short waves a retarding field electron discharge tube is provided and is so designed and arranged in circuit with other receiving apparatus as to collect the incoming energy on a certain electrode or electrodes of the tube. In this way a given electrode or set of electrodes is arranged to possess the dual function of a receiving antenna system and of a device for repelling electrons in the opposite direction to that of the electronic emission. In one embodiment of my invention these antennas may be made non-directional in their receiving characteristics, while in another embodiment a very strong directional characteristic may be obtained.

It is an object of my invention to provide a radio receiving system employing retarding field detector tubes either for directional or non-directional radio reception. It is another object of my invention to so arrange the elements of a retarding field tube as to employ the retarding field electrodes within the tube for collecting the received signalling energy.

Other objects and advantages of my invention will become apparent upon review of the following detailed description when considered in connection with the accompanying drawing in which

Figure 1 shows schematically an arrangement of a retarding field tube in the focus of a parabolic reflector, and

Fig. 2 shows another embodiment of my invention in which the retarding field tube can be made to operate independently of an outside reflector.

Exhaustive research regarding the functioning of reception and rectification in a retarding-field or electron-oscillation tube has demonstrated that demodulation is ascribable to the non-linear internal resistance of the tube, or in other words, to the non-linear characteristic connecting the current and the voltage of such a retarding-field tube. This non-linear characteristic exists when aperiodic reception of oscillations is involved, even though the frequency is far higher than the electron transit times. The non-linear characteristic holds, also, when receiving ultra-short waves having a frequency equal to or a

multiple of the frequency of oscillation of electrons of the retarding field tube. Invariably demodulation is brought about in the retarding-electrode circuit, and the modulation currents obtained from the ultra-short wave carrier may be taken off at will in the retarding-electrode circuit or else in the grid circuit into which they are fed by means of current transference. From a proper understanding of this situation, one important conclusion is reached, namely, that the high frequency voltages induced by the ultra-short wave carrier in a suitable receiver antenna must be impressed upon the retarder electrode itself in order to obtain the most efficient detection.

When working with radio waves of the order of 1 meter in length, it is an easy matter to couple the antenna circuit to the input circuit of an electron discharge tube. The energy collection may be made by a complex and somewhat sizable array of directional antennas if desired. Also, by taking suitable well-known precautions, as by the use of a coaxial cable, the energy may be transferred to a relatively remote receiver before detection.

Upon reducing the wave length to about 1 decimeter, it is imperative that further precautions be taken in the design of the receiving system. In fact, it becomes almost necessary to apply the received energy directly to the retard electrode. A system so arranged will first be described.

Referring to Fig. 1, I show a conventional form of retarding field tube 3 comprising a linear cathode 4, anodes 5 and an intermediate electrode 6 of grid or coil construction. The grid may be a wound wire of sufficient rigidity so as to make it unnecessary to attach separate convolutions to a supporting post. The circuit arrangement for this tube includes a source of direct current potential 7 which renders the grid very highly positive with respect to the potential of the cathode 4. The grid circuit includes a resistor 8 and the primary coil of a transformer T. The secondary winding of this transformer may be connected to any utilization device such as a set of headphones 9. A connection is made from the negative side of the battery 7 through a resistor 10 in parallel with a capacitor 11 and thence to the anodes 5. The resistor 10 has a very high impedance like an ordinary grid leak resistor, but in this case the variations in potential applied to the anodes will produce differing voltages across the resistor 10. The cathode 4

may be heated by any convenient source of energy such as that shown at 11.

In order to collect as much radiant energy as possible and to concentrate the same on the outer surfaces of the anodes 5 the parabolic reflector 12 may be used. Without this reflector it is evident that the characteristics of the receiver would be non-directional. However, in the case illustrated in Fig. 1, an incoming radio wave having the same directivity as that of the axis of the parabola will be reflected upon the outer surfaces of the anode members 5, thereby varying the instantaneous potential thereof with respect to the potential of the cathode.

In the operation of this device as a receiving detector electronic emission from the cathode through the mesh of the high potential grid 6 will result in more or less of the electrons being collected by the anode members 5. If the number of electrons so collected is increased, the anodes become more negative. There is also a tendency to produce a drop of potential in the grid leak resistor 10. Hence, there will be a flow of current through this resistor and a simultaneous reduction in the amplitude of the current flow in the grid circuit. This is true on the theory that the electronic emission from the cathode remains constant. If, then, the current flow in the grid circuit is so varied in response to the incoming energy, it is evident that this current will vary in accordance with the modulations to be detected. Hence, it is possible to utilize the detected and rectified modulation energy in any convenient circuit such as that which includes the secondary of the transformer T and the headphones 9.

While the anode members 5 have been shown as two coaxial cylinders connected together by a lead 13 of a suitable length for obtaining oscillations, it is, in fact, possible to carry out the same idea in a somewhat simpler manner by using a single cylindrical anode member. When two anodes are used as shown, it is preferable that connection be made therewith through a yoke circuit 13 such that the junction point 14 is positioned in an oscillatory node. From this nodal point to each anode the circuit should preferably be of a quarter wave length.

Referring now to Fig. 2, I show an entirely different system which is suitable for operation without the aid of a parabolic reflector. The directional characteristics of this system are obtained by the construction of the tube itself. The tube envelope 15 in this case contains a cathode K of plate formation where the electron emitting surface has a relatively large area. This area may be coated with any suitable oxide or other material such as will produce high electron emissivity.

Within the tube I also dispose a grid G and an antenna structure consisting of separate and distinct co-planar dipoles A₁, A₂ and A₃. The upper arms of the dipoles A₁ and A₃ are connected together and to the lower arm of the antenna dipole A₂. In like manner the lower arms of the dipoles A₁ and A₃ are connected together and to the upper arm of the dipole A₂. These dipoles are preferably spaced apart by as much as a half wave length. The plane in which they lie is perpendicular to the direction of the incoming radio wave. The wave itself is permitted to travel through an electrode H of grid formation but with the conductors thereof all lying parallel to one another and at right angles to the linear direction of each dipole.

This retarding field tube is supplied with suitable potentials as from a high potential source 16 which connects through a portion of the potentiometer 17 to the grid G by way of the primary winding of a transformer T. The cathode 5 is suitably heated by a source of current 18. If desired, the cathode may be of the indirectly heated type or it may be in the form of a filament positioned in such manner that it will offer a large emissive surface facing toward the grid 10 G. Another portion of the direct current source 19 interconnects the portions 16 and 18 and furnishes suitable potential through a potentiometer W, a tap from which may be used to supply a potential to the conductor L for enabling the 15 dipole antennas to act as retard electrodes. Preferably two conductors L are employed, one for feeding the antenna arms of one set, the other for feeding to the antenna arms which are excited in phase opposition by the incoming wave. 20 The common conductor 20 is connected to the leads L preferably at a nodal point of radio wave excitation of the dipoles.

The potentiometer W may be bridged, if desired, by a capacitor C. Another potentiometer 25 21 placed across the battery portions 18 and 19 serves to supply suitable potential to the electrode H, the function of which will presently be explained.

Now, in order that a retarding field may be 30 set up between the antenna system and the grid G, the antennas must be impressed with a potential which is only slightly positive or negative with respect to that of the cathode. The tap on the potentiometer W permits of this adjustment 35 to optimum conditions for rectification. The primary consideration in making this adjustment is to draw electrons through the grid and approximately to the plane in which the dipole antennas lie. However, the dipoles themselves are 40 so far apart that it would be impossible to arrest all of the electrons within a given plane. In order to smooth out the front of the retarding field the grid H is provided. The potential applied to this grid can be varied by means of a tap 45 on the potentiometer 21.

When suitable adjustments have been made in the potentials applied to the various electrodes of this tube, it will be found that the working point in the tube lies on the lower knee or bend 50 of the retarding field characteristic. The homogeneous distribution of the field inside the electron oscillation space is obtained largely by means of the adjustments of potential applied to the electrode H as has heretofore been explained. 55 Thus, practically all of the electrons which fly through the grid G are compelled to reverse their flight in one and the same plane which, according to the conditions of operation, may be situated either in front of or behind the 60 plane of the antennas.

In order that the incoming or signal waves may reach the retarder electrode unimpededly, that is, in order that they may not be shielded or screened by H, it is necessary to design the co-operating electrode H to act as a polarizing grid having wires extending at right angles to the receiver dipoles A₁, A₃. Preferably the distance between grid G and the antenna system A is so chosen that the grid surface acts as a reflector, 70 with the incidental result that the focusing or concentration power of the receiver antenna system A is boosted.

If the receiving dipoles A₁ to A₃ are so interconnected by way of L that the main direction 75

of the radiation diagram lies in the plane of the drawing, then the auxiliary electrode H naturally could consist of solid metal and conjointly with grid G will act as a wave channel.

- 5 In the drawing the directional receiver tube is shown incorporated in a suitable receiver circuit organization. The grid voltage E_g for the object of tuning the electron oscillations is variable, and in the grid lead is included the transformer 10 T which feeds the modulation variations derived from the tube to a radio frequency or audio frequency amplifier. The potential of the antenna system by way of the high ohm leak resistance W adjusts itself spontaneously to the point of 15 intersection of the straight resistance line and the tube characteristic. The said leak is shunted by the condenser C so far as the modulation potentials are concerned.

20 The electrons emitted from the cathode K execute to-and-fro oscillations about the positive grid G and they cause the antenna system of the retarding field tube to be regeneratively excited. At the same time the resonance potentials induced by the incoming carrier oscillations in the 25 free ends of the receiving dipoles are rectified, and they result in the retarder electrode circuit in a rectified current which by virtue of current distribution is taken over in the grid circuit and which may be conducted away through transformer T. The regeneration and rectification 30 actions occurring in the new tube here disclosed, therefore, do not differ from those in the customary retarder field receiver circuit organizations.

35 It may finally be noted that the principle underlying this invention is capable of quite a number of modified solutions which, however, are basically the same as the one incorporated in the exemplified arrangement hereinbefore disclosed. For instance, the antenna system could consist 40 of any desired number of constituent or separate dipoles mounted adjacent or posteriorly of one another, say, in a so-called Christmas tree antenna arrangement as known in the prior art. Such modification of the system does not affect, 45 however, the basic principle of the invention.

I claim:

1. A radio receiver for ultra-short waves comprising an electron discharge tube having a cathode, a grid carried at a highly positive potential with respect to the cathode, an antenna system mounted within said tube and in the path of electronic emission beyond the grid, said antenna system comprising means including a plurality of co-planar dipole antennas disposed 50 within the range of influence of radiant energy, and means for maintaining a high negative bias on said antennas with respect to said grid, thereby to reverse the direction of flight of electrons emitted by said cathode.

60 2. A receiver in accordance with claim 1 and having an additional electrode disposed in the path of the radiant energy, said electrode having a grid formation of parallel conductors through which said radiant energy is enabled to pass before reaching the antenna system.

65 3. A retarding field discharge tube for a radio receiver comprising an envelope, a cathode of relatively large emissive area, a grid having means connected thereto for producing a highly positive bias thereon with respect to the cathode, a retarding electrode situated beyond the grid with respect to the cathode and constituted by a plurality of dipole antennas having their linear axes lying parallel to one another and in a plane 70 substantially perpendicular to the principal axis

of flight of electrons emitted by said cathode and projected through the mesh of said grid, an auxiliary retard electrode maintained at a potential somewhat more positive than the cathode and further removed from said grid than the 5 antennas, a circuit interconnecting the grid and cathode, another circuit interconnecting the antennas and cathode and means for carrying said antennas at a suitable bias potential with respect to the cathode for producing current variations of modulation frequencies in the respective circuits of said grid and said antennas in response to modulated ultra-high frequency energy collected by said antennas.

4. A device in accordance with claim 3 and 15 further characterized in that said auxiliary electrode is constituted by a grid having parallel-disposed conductors through which the received radiant energy has unimpeded access to said 20 antennas.

5. A device in accordance with claim 3 and further characterized in that said grid is disposed a predetermined distance behind the antennas, viewing the structure from the direction of the source of the incoming wave, and said 25 grid reflects said wave back to said antennas thereby to increase the response to signals.

6. The method of collecting and detecting ultra-high frequency radiant energy in a retarding field discharge device having a cathode and 30 at least three reticulated electrodes which comprises passing the radiant energy through the mesh of one of said reticulated electrodes while maintaining a somewhat positive bias thereon with respect to the cathode, collecting said energy on a second reticulated electrode, causing the last said electrode to variably repel the free electrons of said discharge device, subjecting a third one of said reticulated electrodes to a high positive bias relative to the cathode and causing 35 the emission from said cathode to be maintained substantially constant while the currents between the third reticulated electrode and the cathode are varied in response to modulations of said radiant energy.

7. A radio receiver comprising a parabolic reflector, a retarding field discharge tube disposed in the focus of said parabolic reflector, said tube having a linear cathode, a grid conformed to a cylindrical surface concentric with 50 the cathode, and an outermost electrode also concentric with the cathode, an operating potential source having connections with the several electrodes such that the tube possesses a retarding field operating characteristic, means 55 for impressing radiant energy on the exterior surface of the outermost electrode of said tube, and means for varying the current flow between that electrode and another electrode of said tube in accordance with modulations of the received 60 ultra-high frequency energy.

8. A device for ultra-short wave reception comprising an electron discharge tube having a cathode, a reticulated electrode and a plurality of other electrodes, means for applying to said 65 reticulated electrode a potential which is highly positive with respect to said cathode, means for enabling two of said other electrodes to act as complementary energy collectors, potential biasing means for causing the last said electrodes to 70 serve also as retard electrodes, and a signal-sensing device in circuit between said reticulated electrode and said cathode.

9. A device for ultra-short wave reception comprising an electron discharge tube having a 75

cathode, a reticulated electrode and a retarding field electrode, means for energizing said reticulated electrode in a highly positive sense relative to the cathode and to the retarding field electrode, means for disposing portions of said retarding field electrode in two distinct but interconnected sets of radiant energy-collecting members, means for impressing a slightly positive bias on said retard electrodes with respect to the cathode, and means whereby the energy collect-

ing members of one set are energized co-phasally and in phase opposition to the phase of the instantaneous potential with which the members of the other set are energized.

10. A device in accordance with claim 9 and 5 including a wave-polarizing grid interposed between said retarding field electrode and the source of incoming radiant energy.

HANS ERICH HOLLMANN. 10
